US00D947904S

(12) **United States Design Patent** (10) Patent No.: **US D947,904 S**
Anderson et al. (45) Date of Patent: ** Apr. 5, 2022

(54) **COMBINATION WEIGHT MEMBER AND FLOOR SCRAPER MACHINE**

(71) Applicant: **Anderson Innovations, LLC**, Two Harbors, MN (US)

(72) Inventors: **Martin L. Anderson**, Two Harbors, MN (US); **Joseph M. Anderson**, Duluth, MN (US); **Mason Lloyd Anderson**, Harris, MN (US)

(73) Assignee: **Anderson Innovations, LLC**, Two Harbors, MN (US)

(**) Term: **15 Years**

(21) Appl. No.: **29/676,250**

(22) Filed: **Jan. 9, 2019**

(51) LOC (13) Cl. **15-03**

(52) U.S. Cl. USPC **D15/28; D15/10**

(58) **Field of Classification Search**

USPC D15/28, 10
 CPC E04G 23/006; E04G 23/00; A47L 13/02

(57) **CLAIM**

The ornamental design for a combination weight member and floor scraper machine, as shown and described.

DESCRIPTION

FIG. 1 is an upper perspective view of a combination weight member and floor scraper machine showing our new design, the portions shown in broken line forming no part of the claimed design;

FIG. 2 is a lower perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
